J. G. L. FORSTER

BOOKKEEPER'S AND ACCOUNTANT'S GUIDE

Filed May 28, 1920

Inventor
John G. L. Forster
BY
Conrad A. Deltard
his Attorney

UNITED STATES PATENT OFFICE.

JOHN G. L. FORSTER, OF NEW YORK, N. Y.

BOOKKEEPER'S AND ACCOUNTANT'S GUIDE.

Application filed May 28, 1920. Serial No. 384,945.

To all whom it may concern:

Be it known that I, JOHN G. L. FORSTER, a citizen of the United States, residing at the city of New York, borough of Manhattan, county and State of New York, have invented certain new and useful Improvements in Bookkeepers' and Accountants' Guides, of which the following is a full, clear, and exact specification.

10 My invention relates to improvements in means for enabling bookkeepers, accountants and others required to add long columns of figures in books or upon sheets, conveniently and accurately, and without danger 15 of including in one column the figures or members located in an adjoining column, and also to insure the entering of the figures in the appropriate column.

Further, said invention has for its object 20 to provide a device of the character specified which may be readily adapted for use in connection with short as well as long columns of figures.

Further, said invention has for its object 25 to provide a device of the character specified which is convenient to use, and which may be readily extended or adjusted so as to permit of the guide to be used in connection with columns of varying length.

30 Further, said invention has for its object to provide a device of the character specified comprising a support and an extensible guide member secured to or carried thereby, and means whereby said support may be

35 readily adjusted to or formed as an integral part of a support adapted for securement to a blotter or other convenient holding means.

Other objects will in part be obvious and 40 in part be pointed out hereinafter.

To the attainment of the aforesaid objects and ends my invention consists in the novel details of construction, and in the combination, connection and arrangement 45 of parts hereafter more fully described and then pointed out in the claims.

In the accompanying drawings forming part of this specification, wherein like numerals of reference indicate like parts,—

50 Figure 1 is a detail perspective view showing the method of using the device;

Fig. 2 is a plan or face view showing one form of device constructed according to and embodying my said invention;

Fig. 3 is an edge view, looking in the direction of the arrow *a* Fig. 2, and

Fig. 4 is a plan or face view showing a modified construction.

In said drawings 10 designates a support which is herein shown as a flat triangular corner pocket or receptacle, and provided with fastening means 11 whereby the same may be secured to one corner of a blotter or other convenient device. From one end of said triangular support 10 extends upwardly a longitudinal member 12, which is preferably formed integrally with said support 10, and provided at its outer end with a loop 13.

14 denotes a co-operating longitudinal member which corresponds in outline with the longitudinal member 12, and has its free outer end loosely embraced by the loop 13, formed at the outer end of the member 12,

and is provided at its inner end with a similar loop 15, which embraces the longitudinal member 12 intermediate the support 10 and the loop 13, so as to permit of the extending of the guide to enable the user to employ the device in connection with columns of figures of varying heights.

The longitudinal member 14 is provided adjacent to its free end with a recess or indentation 16 adapted to receive the point of a pen or pencil whereby to facilitate the movement of the longitudinal member 14 inwardly or outwardly upon the rigid longitudinal member 12.

At Fig. 4 the support 10^a is formed as a longitudinal member, from one end of which extends outwardly, and at right angles thereto, a rigid member 12^a carrying the slideable member 14^a, as shown and described in connection with the main construction. In this construction the slideable member 14^a has its extreme end turned upwardly at right angles to the body thereof to form a finger portion 16^a whereby to move said slideable member 14^a back and forth.

The support 10^a is provided with a longitudinal fastener 17 having prongs 18 which extend through said support 10^a, and are adapted to pass through the blotter whereby to permit of the securing of said support 10^a to said blotter or other convenient support.

The operation of the device is largely obvious. To use the same it merely becomes necessary to place the holder, blotter or other

device, as the case may be, to which the guide is attached, in position upon the page or sheet adjacent to the lower end thereof, and adjust the guide, comprising the members 12 and 14, parallel with, and to one side of the column of figures to be added, and then adjust the extensible member 14 to a height corresponding with the height of the column to be added.

10 It will of course, be obvious that the guide comprising the members 12 and 14 may be provided with a support of any desired shape and size, and that when the support is made larger the device may be used without a blotter.

Having thus described my invention what I claim and desire to secure by Letters Patent is:—

1. A device of the character described, comprising a relatively thin, flat support, means for securing the same to one end of a blotter or analogous article, and a guide member disposed in the same transverse plane with said support, and extending therefrom; said guide member comprising a part rigid with said support, and a co-operating part movably mounted with respect to said rigid part, substantially as specified.

30 2. A device of the character described, comprising a relatively thin, flat support adapted to receive one end of a blotter or analogous article; and a guide member disposed in the same horizontal plane with said support and extending therefrom; said guide member comprising a part rigid with said support, and a co-operating part slidably mounted with respect to said rigid part, substantially as specified.

40 3. A device of the character described comprising a relatively, thin flat support, a flat receptacle thereon adapted to receive and hold a blotter or the like, and a guide member extending from one edge of said support and comprising a longitudinal member secured at one end to said support and a co-operating member corresponding to said longitudinal member and movable with respect

thereto, and means on one end of each of said members loosely embracing the other of said members, substantially as specified.

4. A device of the character described comprising a relatively thin flat support, adapted to receive a blotter or analogous article, and a guide member extending outwardly from one edge of said support and comprising a longitudinal member rigidly secured at one end to said support, a co-operating member corresponding in shape to said first named longitudinal member and movable with respect thereto, and loops arranged at the adjoining ends of said longitudinal members, each embracing the other of said members, whereby to permit of the movement of one of said members with respect to the other, and to limit the movement of said movable member, substantially as specified.

5. A device of the character described, comprising a relatively thin flat support, a flat receptacle thereon, adapted to receive and hold one end of a blotter or analogous article; and a guide arranged at one edge of said support and comprising a longitudinal member formed integrally with said support, a second longitudinal member carried by said first-named longitudinal member and movable with respect thereto, and means arranged upon the adjoining ends of each of said longitudinal members and each embracing the other of said longitudinal members, whereby to permit of the movement of said second named longitudinal member with respect to said first named longitudinal member and to limit the outward movement of said second named longitudinal member, substantially as specified.

Signed at the city of New York, county and State of New York, this 13th day of September, one thousand nine hundred and nineteen.

JOHN G. L. FORSTER.
